UNITED STATES PATENT OFFICE

FRANCIS BERRY McILROY, OF HAMMOND, INDIANA

FOLDER FOR ANTISQUEAK MATERIAL

Application filed July 8, 1930. Serial No. 466,543.

This invention relates to improvements in the design and construction of a folder for anti-squeak material, the primary object being to provide a type of folder which ⁵ jointly carries cores or beads and enfolds them within the outer edges of a suitable fabric, thus creating an anti-squeak material having edges increased in thickness by the insertion of such cores or beads and at the same time effecting a channel or concave ¹⁰ through the agency of which rivet heads are maintained in a position which assures non-engagement with other relative metal parts such as the hood of an automobile, etc., ¹⁵

With these and other objects in view as will appear as the description proceeds, the invention consists in the design, construction and arrangement of parts as hereinafter more specifically set forth, claimed and ²⁰ shown in the accompanying drawings forming a part of this present application and in which—

Figure 1 shows a perspective view of the top of the folder.

Figure 2 shows the outlet of the folder.

Figure 3 shows a perspective view of the under side of the folder.

Figure 4 shows the entrance of the folder.

Figure 5 shows cross-sections at various ³⁰ points in the folder.

Figure 6 shows various stages of the material being folded.

Figure 7 shows a type of finished anti-squeak material.

Referring more in detail to the accompanying drawings in which similar characters represent corresponding parts throughout the several views, it will be seen that the invention consists of a casing 10 flat in cross-section at the entrance 11 and tapering until oval in cross-section at the outlet 12.

Constructed at the entrance of the casing 10, is a flat or plane section 13, said plane section being slightly narrower than the entrance 11 as shown at 14 in Figure 4. On the upper side and extending across the plane section 13 are bands 15, these bands being slightly above the plane section as shown in Figure 4, allowing passage to the material which is to be folded.

Constructed on the under side of the casing 10 are tubes 16, spaced a suitable distance apart. These tubes extend from the entrance 11 toward the outlet 12, said tubes being disposed to the inside upon reaching that portion of the casing oval in cross-section as shown at B and C, Figure 5.

At the top of the casing 10, a slot 17 is cut which facilitates threading the material through the folder.

The folder is provided with a suitable flange 18 providing means for securing the device to sewing machines.

To effect folding a suitable strip of fabric is first inserted between the flat section 13 and the bands 15, one edge of the fabric being folded under around the edge 28. Continuing to the entrance 11, the tapered casing 10 effects continuous stages of folding as shown at 20, 21, 22 and 23 Figure 6.

During this period of folding, suitable cores which lead through the tubes 16, are positioned at the edges of the fabric and folded therein, said fabric and cores being simultaneously drawn through the folder.

Positioned in the outlet 12 of the casing and extending inwardly to the tubes 16 is a horizontal flange 19, through the agency of which the rough edge 24 is folded under the already folded edge 25, as the material is drawn through the casing, leaving no rough edges exposed to become frayed.

As already disclosed, the action of the folder creates an anti-squeak web having edges increased in thickness through the insertion ⁸⁵ of cores effecting a channel or concave between such cores.

A further preferred feature is that the folder creates a multipleply thickness in the base of the anti-squeak, i. e. the grooved section 26 created between the longitudinal cores 27 as shown in Fig. 7.

The folder may be constructed in varying widths as governed by the size of the required anti-squeak.

It is believed that the design, construction and arrangement of the invention are apparent from the foregoing paragraphs taken in conjunction with the accompanying drawings without further detailed description.

While the preferred embodiment of the invention has been disclosed, it is understood that minor changes in the details of construction, combination and arrangement of co-operating elements may be resorted to within the scope of what is claimed, without departing from the spirit of the invention.

What I claim is:

1. In a device of the character described, 10 a casing flat in cross-section at the entrance and tapering until oval in cross-section at the outlet and a flat guide plate extending longitudinally from the entrance of the casing, said guide plate being slightly narrower 15 than the entrance.
2. In a device of the character described, a casing flat in cross-section at the entrance and tapering until oval in cross-section at the outlet, a guide plate extending longitudinally from the entrance of the casing, said 20 guide plate being slightly narrower than the entrance, and bands extending across the guide plate for holding the material thereon.
3. In a device of the character described, a casing flat in cross-section at the entrance and tapering until oval in cross-section at the outlet, and core insertion tubes on the outer side of said casing extending from the 25 entrance and entering the casing a suitable distance from the outlet.
4. In a device of the character described, a casing flat in cross-section at the entrance and tapering until oval in cross-section at 30 the outlet, core insertion tubes on the outer side of said casing extending from the entrance and entering the casing a suitable distance from the outlet, and a flange disposed in the outlet end of said casing, extending 35 from the outlet to the ends of said core tubes.

In testimony whereof I affix my signature.
FRANCIS BERRY McILROY.
